UNITED STATES PATENT OFFICE.

JOHN COCKBAIN BRIGGS, OF CUMBERLAND, ENGLAND, ASSIGNOR TO AERO & GENERAL PUMP MANUFACTURING COMPANY, LIMITED.

PUMP.

1,338,118.

Specification of Letters Patent. Patented Apr. 27, 1920.

Application filed July 1, 1919. Serial No. 307,983.

To all whom it may concern:

Be it known that I, JOHN COCKBAIN BRIGGS, a subject of the King of Great Britain, residing at East View, Workington, 5 Cumberland, England, have invented new and useful Improvements in or Relating to Pumps, of which the following is a specification.

This invention relates to improvements in reciprocating pumps and it consists in the combination with a pump plunger of mechanism for imparting to the latter a reciprocating and turning movement, such mechanism comprising a crank operatively connected to the plunger and carried on a shaft located at right angles to the path of reciprocation of the said plunger. To permit of the combined movements of rotation and reciprocation taking place the crank-pin is arranged to slide longitudinally in the crank-shaft and the said sliding movement of the pin can be utilized as an auxiliary pump-plunger for forcing lubricant to the crank bearings. As will be understood the plunger is furnished with lateral ports which coöperate with ports in the cylinder for suction and discharge.

The pump is particularly suitable for use as a petrol pump on aero-engines in which the petrol is fed to the engine under pressure; and a pump for this purpose is illustrated in the accompanying drawing, in which:—

Figure 1 is a longitudinal section, and Fig. 2 is a horizontal section on the line 2—2, Fig. 1.

Figs. 3 and 4 are respectively vertical sections on the lines 3—3 and 4—4, Fig. 1 approximately.

Fig. 5 is a central vertical section of the lower part of the pump but with the parts in a different position from that shown in Fig. 1.

A indicates the pump plunger arranged to turn and reciprocate in the cylinder B which is carried on the bracket C. The bracket C is connected to the driving engine or motor by a flange D, and it also serves as a bearing for the crank-shaft E designed to be driven in any suitable manner. The inner end of the said crank-shaft is coned at F and is held in engagement with a coned seating in the bracket C by a spring G compressed between a collar H pinned to the crank-shaft, and the bottom of the cupped

end of the bracket C. A ball bearing consisting of balls I and race-plates J is interposed between the rotating collar H and the end of the stationary spring G.

K indicates the crank-pin which is connected to the plunger A by a pivot pin L so as to swing transversely to the axis of the plunger, the said pin also being capable of sliding longitudinally in the end of the crank-shaft E. By this means, during the rotation of the said crank-shaft and the resulting reciprocation and turning movement of the pump plunger, the crank-pin K is caused to reciprocate in the end of the crank-shaft, and this reciprocating movement of the crank-pin is used to force lubricant to the crank bearings. For this purpose a suction opening M for oil is provided in the bracket C, and is adapted to communicate with an arcuate port N in the crank-shaft at the moment when the crank-pin K is sliding outwardly on its suction stroke. The crank-pin is hollow so that the oil can reach the pivot pin L, and intermediate the ends of the said crank-pin is a discharge opening O which, during the compression stroke of the crank-pin in the crank-shaft, communicates with a discharge conduit P in the latter so that oil is forced into an annular groove Q in the crank-shaft bearing and from thence spreads over the bearing surface. The said groove Q also prevents or reduces the leakage of petrol past the coned end F of the crank-shaft E, the oil pressure in the groove being maintained in excess of the fluid pressure in the pumping cylinder by means of the auxiliary plunger K; or the suction opening M may be connected directly to the groove Q, and oil fed at high pressure through the said opening.

The pump is double acting and ports, such as R in the skirts constituting each end of the plunger A, coöperate with ports, such as S, in the cylinder B, for the purpose of suction and discharge, as indicated clearly in Figs. 1, 3 and 4. T is the suction opening for the pump and U, is the discharge opening. The plunger skirts can be provided with longitudinal slots, such as V, to insure resilience of the said skirts and so that they function as scraper rings.

Caps W are provided at each end of the cylinder and are inwardly cupped to reduce the clearance at each end of the plunger.

Having now particularly described and ascertained the nature of the said invention and in what manner the same is to be performed, I declare that what I claim is:—

- 5 1. In a reciprocating pump, the combination with a plunger, of means for imparting a combined reciprocating and turning motion to the said plunger, said means consisting of a shaft extending at right angles to the path of reciprocation of the plunger, and a crank pin having one of its ends slid-

ably mounted in one end of the shaft and its other end pivotally connected to the pump plunger.

2. A pump as claimed in claim 1, wherein 15 the crank pin is hollow and a suction opening in the crank-shaft is provided adjacent the free end of the crank pin, and a discharge opening in the crank-shaft is provided intermediate the ends of the crank- 20 pin, for the purpose described.

JOHN COCKBAIN BRIGGS.
